FIG. 5.

INVENTOR,
FREDERICK S. McCULLOUGH
BY Bates and Macklin,
ATTYS.

UNITED STATES PATENT OFFICE.

FREDERICK S. McCULLOUGH, OF CLEVELAND, OHIO, ASSIGNOR TO GLENN L. MARTIN,
OF CLEVELAND, OHIO.

APPARATUS FOR DIRECTIVE TRANSMISSION OF ELECTROMAGNETIC WAVES.

1,403,700.

Specification of Letters Patent. Patented Jan. 17, 1922.

Application filed October 30, 1916. Serial No. 128,375.

To all whom it may concern:

Be it known that I, FREDERICK S. McCULLOUGH, a citizen of the United States, residing at Cleveland, in the county of 5 Cuyahoga and State of Ohio, have invented a certain new and useful Improvement in Apparatus for Directive Transmission of Electromagnetic Waves, of which the following is a full, clear, and exact description, 10 reference being had to the accompanying drawings.

This invention relates to an improved system of transmission of electro-magnetic waves for purposes of wireless communication, signaling, etc. The general object is 15 to increase the efficiency of and to simplify such apparatus.

A more specific object of this invention is to so construct the apparatus that it may 20 be effectively used for actuating selectively one or more of a plurality of receiving devices by directive transmission of electro-magnet waves from one or more transmitting apparatus. The invention is particularly 25 useful for signaling successively individual members of a series of receiving devices the transmitting device being so arranged as to travel in a pathway leading past said receiving devices.

Another specific object of the invention is 30 to arrange the apparatus that it may be well adapted for use in a system including a plurality of receiving members located at intervals along a trackway or guideway and 35 in close proximity thereto, while a coaxing transmitting device may communicate selectively with the receiving devices as it is moved along the trackway or guideway past the same.

The manner of accomplishing the above 40 and other objects of my invention is set forth in the following description which refers to the drawings illustrating a preferred embodiment thereof. The essential 45 characteristics of the present invention are set forth in the claims.

I have shown, in the drawings, illustrations of my invention in diagrammatic form, in order that it may be more readily understood, as it is apparent that those skilled 50 in the art may readily embody the invention with proper mechanical devices corresponding to the diagrammatic illustrations.

In the drawings, Fig. 1 is a diagrammatic 55 view illustrating a simple form of trans-

mission and receiving apparatus; Fig. 2 is a similar view showing a modified form of receiving apparatus; Figs. 3 and 4 are a side elevation and a front elevation respectively, of a particular form of parabolic-shaped capacity members; Fig. 5 is a view showing a series of receiving station and a transmission device coaxing therewith and adapted to travel in parallel relation thereto. In this figure the transmitting device is illustrated in solid lines in the intermediate position, and in dot and dash lines in the other positions coaxing with other receiving stations. Fig. 6 illustrates a slightly modified form of transmitting and 60 receiving stations adapted to be used in a similar manner. Fig. 7 is a cross-section on an enlarged scale of the tube 40 showing the wire 55 in heating contact with the glass.

Referring to Fig. 1, 10 indicates a suitable high frequency generator which is illustrative of any means for generating electro-magnetic waves of high frequency. One pole of this generator is shown as connected to the ground 12 by a wire 13. From 75 the other pole a wire 14 leads to a coil 16 providing a variable inductance, the contact 17 being movable along the same. This inductance is shown as connected with a capacity member indicated at 20, which is 80 preferably of the form shown in Figs. 3 and 4, and which will be later more specifically described.

By arranging the capacity member 20 or the induction portion 16, or both, so that 85 they may be adjusted, they may be brought into proper proportion to the desired wave length. The frequency of the generator may be varied by changing its speed.

At 25 is indicated a receiving capacity 90 similar to the transmitting capacity 20 and connected by a wire 30 with a suitable receiver indicated at 32, and connected to the ground 12 by a wire 33. The telephone at 100 32 is merely symbolical of any suitable receiving apparatus, and its diaphragm is not intended to vibrate at radio frequencies.

Referring to Fig. 2 and Fig. 7, in which is illustrated an apparatus more particularly adapted for relay signaling by directive 105 transmission of electromagnetic waves, the transmitting device is substantially the same as shown in Fig. 1, while the receiving device is shown as comprising the receiving capacity 25 and a hot cathode tube 40 hav- 110

ing connections 41 and 42 leading from the capacity to the cathode tube and thence to the ground respectively. Within this tube are a plurality of minute wires 44. Mounted 5 adjacent the same is plate 45 connected by a separate wire 46 with a source of current 47 leading through a magnetic relay 48, wire 43, and thence to the wire 41. The relay 48 is shown as actuating an armature 49

10 governing an independent circuit 50 having a source of current 51 and controlling a signal indicated at 52, which may represent any indicating device, shown for example, as any electric light bulb.

15 The tube 40 is practically evacuated, but may contain a residuum of an inert gas, such as nitrogen. The coil of wire, 55, surrounds this tube and is connected with the high frequency alternating current generator 56. In 20 circuit with the generator and the coil is the variable resistance 58, for regulating the current in the circuit. The frequency of the generator 56 may be varied by changing its speed. A branch circuit, 57, runs to the 25 wire 42.

The rapidly alternating electrification or changing of the currents in the coil 55 causes the latter to become heated. This heated coil surrounding and substantially 30 in contact with the glass tube or globe, causes the latter to become heated as the result of radiation and conduction of such heat. The filament or wires 44 are heated by the charge effect placed upon the capacity member 25, which creates current flowing through wires 44 in connection with the ground 12, making a complete circuit through the transmitter and receiver. In 35 this manner, therefore, it will be understood that a maximum emission of electrons is obtained.

The frequency of generator 56 should be the same as that of generator 10 at the transmitting station, and a rapidly oscillating 40 field is created in the tube, within the coil 55. Under these circumstances, when the waves from the transmitting station are received at the receiving station on the receiving capacity 25, and the oscillations are 45 transmitted by the wire 41 to the wire or wires 44 in the tube, the flow of electrons between the wire or wires 44 and the plate 45 is increased to an extent sufficient to permit a flow of current in the circuit including 50 the battery 47 and relay 48 great enough to operate the relay 48, so that current will flow in the circuit containing the indicating device 52, and cause the latter to give a signal.

The parabolic capacity device, illustrated 55 particularly in Figs. 3 and 4, is shown as made up of a continuous flat metal surface warped into the shape of a parabolic reflector. This flat surface preferably comprises a thin ribbon of metal connected 60 at each end to conductors 60 and bent re-

peatedly upon itself in a tortuous path, forming a series of loops 62 each connected at one end with the loop nearer the wire 60 and at the other end with the loop next away from that wire, as indicated at 63, and each of these ribbons lying in an imaginary surface of the reflector. This disposition of the conductor also reduces the inductance to a minimum.

A capacity such as just described has been 70 found by experiment to be very sensitive and effective when used with a receiving apparatus.

In carrying out the specific object of actuating a plurality of receiving devices by 75 directive transmission of electro-magnetic waves from a station having its capacity traveling in a pathway in parallel relation to the capacities of the receiving devices and without interference. I have arranged 80 the system shown in Fig. 5 in which the generator 10, inductance 16 and ground 12 are illustrated substantially as in Fig. 1 and in which the capacity 70 may be of any 85 desired shape or form. 90

The capacities 75 are adapted to receive impulses from the directive capacity 70 only when the capacity 70 is in proximity or position substantially opposite one of the capacities 75. 95

In this Fig. 5 the directive transmission device is adapted to be moved along a pathway and as it comes into the position marked A, which is shown in solid lines, it communicates with the receiving station directly opposite. The positions B and C indicate the sending device in position to 100 transmit impulses to the corresponding receiving stations.

In the arrangement shown in Fig. 5, one 105 terminal of the electro-magnetic generator means is connected with the ground which, furnishing a conductor, renders necessary only one set of capacity members. However, in Fig. 6 is shown a slightly modified 110 arrangement in which the generator 10 has its one terminal connected with the capacity member 70, as above described, while the other terminal is connected with a capacity 115 adapted to receive impulses from a capacity member 85 when the capacity members are brought into the relative positions illustrated in this figure. This particular arrangement is useful in instances where grounding the circuit would tend to misdirect the same, as the capacity member may be made more truly selective if operative 120 only when both capacities are brought into close proximity, as illustrated.

The arrangement of the system just 125 described is particularly useful, for example, in signaling systems for elevators and the like.

The capacity members 70, 75, 80 and 85 are diagrammatically illustrated as flat 130

plates, but, in instances where the distance between the capacity members is comparatively great, capacity members such as illustrated in Figs. 3 and 4 may be used with advantage, as the waves might then be directed toward a particular station which would receive sufficient energy, by reason of the directing action of such a capacity member, to actuate its receiving device while those toward which the capacity member is not directed would receive no impulses sufficient to register.

From the foregoing description it will be seen that I have provided a system and apparatus for wireless transmission, capable of selectively communicating from one or more stations to any of a series of stations and that when the distance between the stations is appreciable, the directive capacity member herein described will function very usefully in controlling the selection of the receiving station.

Having thus described my invention, what I claim is:

1. In a system of wireless transmission, the combination of means for generating electro-magnetic waves, a directive capacity member associated with said means and comprising a conductive flat ribbon bent upon itself in a succession of loops and arranged in the form of a parabolic reflector.

2. In a wireless signaling apparatus, a means for receiving or projecting electro-magnetic waves, comprising a capacity member, made up of a flat conducting element which is oblong in cross section and arranged edge to edge in courses spaced apart.

3. A capacity member for use in a wireless transmission system, consisting of a conductor convoluted into the form of a 40 skeleton paraboloid.

4. A capacity member for use in a wireless transmission system, consisting of a conductor convoluted into the form of a skeleton paraboloid, the conductor being elongated in cross section in the direction of the parabolic surface.

5. A capacity member for use in a wireless transmission system, comprising a skeleton paraboloid consisting of a substantially 50 flat metallic ribbon convoluted into parallel strips with the edges adjacent but separated.

6. In a wireless system, an element consisting of a continuous thin, flat conductor, 55 oblong in cross-section, disposed edge to edge in a series of adjacent courses, said conductor being bent back upon itself in a parabolic surface.

7. In a wireless system, an element consisting of a continuous thin, flat conductor, 60 oblong in cross-section, disposed edge to edge in a series of adjacent courses, the adjacent courses running in opposite directions, in a parabolic surface.

8. In a wireless system, an element consisting of a continuous thin, flat conductor, 65 oblong in cross-section, so disposed in a parabolic surface, as to increase its capacitance and reduce its inductance.

In testimony whereof, I hereunto affix my signature.

FREDERICK S. McCULLOUGH.
